UNITED STATES PATENT OFFICE.

GEORGE STROH, OF SYRACUSE, NEW YORK.

CASTING APPARATUS.

SPECIFICATION forming part of Letters Patent No. 759,569, dated May 10, 1904.

Application filed August 8, 1903. Serial No. 168,749. (No model.)

To all whom it may concern:

Be it known that I, GEORGE STROH, a citizen of the United States, and a resident of Syracuse, in the county of Onondaga, in the State of New York, have invented new and useful Improvements in Casting Apparatus, of which the following, taken in connection with the accompanying drawings, is a full, clear, and exact description.

10 The object of this invention is to provide a simple, inexpensive, and efficient casting apparatus in which the molten metal shall be forced into the die or matrix by means of a pressure-chamber located within the melting-pot, and thus maintained at the same temperature therewith, and a cylinder communicating with said pressure-chamber and a plunger operating in said cylinder, both shielded from the intense heat of the combustion-chamber to guard against overheating said parts and to reduce the temperature thereof sufficiently to keep them in working condition; and to that end the invention consists in the improved construction of the casting apparatus herein-
20 after described, and set forth in the claim.

In the accompanying drawings, Figure 1 is a vertical longitudinal section of a casting apparatus embodying my invention. Fig. 2 is a transverse section on line X X in Fig. 1. 30 Fig. 3 is a horizontal section on line Y Y in Fig. 1, and Fig. 4 is a transverse section on line Z Z in Fig. 1.

Similar letters of reference indicate corresponding parts.

35 *a* represents the melting-pot, which is seated in a combustion-chamber *b*, preferably formed of a surrounding fire-brick structure *c*, through which pass suitable burners *d d* for supplying the requisite heat to the combustion-chamber.

40 *e* denotes the pressure-chamber, which is of cylindrical shape and located within the melting-pot to partake heat therefrom with an equal degree of temperature. This pressure-chamber is provided with a port *f*, through which it receives the molten metal from the melting-pot *a*. The top of the said pressure-chamber is provided with a suitable discharge-nozzle *g*, through which the molten metal is forced from the pressure-chamber into the die

or matrix *h*, seated directly upon the said nozzle.

The melting-pot, with the inclosed pressure-chamber, I form in one piece of cast metal and without any seam at the junction of said parts. The said casting is suspended from the edges 55 of an aperture in a plate *A*, mounted on a metal case *C*, embracing the fire-brick work *c*, which forms the combustion-chamber *b*.

From one end of the pressure-chamber *e* extends a cylinder *i*, in which operates a plunger *j*. To protect the said cylinder and plunger from the intense heat in the combustion-chamber *b*, I form around the said cylinder a cooling-compartment *l* of the form of a shield *n*, extending from the end of the cylinder 65 adjacent to the pressure-chamber to a sufficient distance beyond the opposite end thereof to inclose the plunger *j* where the shield is open to allow air to circulate around the cylinder and piston. The plunger is hollow or 70 formed with a cavity *o*, extending from the outer end of the plunger part way the length thereof to allow the air to circulate in the plunger and prevent its being excessively heated by contact with the molten metal in the 75 pressure-chamber.

D represents a cylinder, which may be charged with either steam or gas or water under pressure. This cylinder is arranged axially in line with the cylinder *i* and is firmly 80 secured to a head on extensions *v* of the top plate *A* and base-plate *B*, as shown in Fig. 1 of the drawings.

p represents the piston, which works in the cylinder *D* and is connected to the plunger *j* 85 by the rod *t*.

I preferably employ in addition to the cylinder *D* a trial-lever *L*, pivoted to a suitable bearing *u* on the extension *v* and connected at one end to the rod *t* and having its free end 90 portion of sufficient length to afford the requisite purchase for moving the plunger. This trial-lever is desired to ascertain if the molten metal is in proper condition to be forced from the pressure-chamber before applying the 95 pressure of the piston *p*.

What I claim as my invention is—
A device of the type set forth comprising a

combustion-chamber, with a pressure-chamber and a melting-pot integrally formed therewith located in said combustion-chamber, with a communication between the pot and pressure-chamber, a shield extending partially the length of the pressure-chamber, and surrounding the sides and bottom thereof and being extended outwardly and in communication with

the atmosphere, a plunger in said pressure-chamber inclosed by said shield, and a nozzle to at the upper end of the pressure-chamber.

GEORGE STROH.
